DESIGN FOR A SLIDER FOR FASTENING ELEMENTS

Alden G. Stevens, Woodbury, Conn., assignor to United States Rubber Products, Inc., New York, N. Y., a corporation of Delaware

Application June 11, 1937, Serial No. 69,791

Term of patent 7 years

To all whom it may concern:

Be it known that I, Alden G. Stevens, a citizen of the United States of America, residing at Woodbury, county of Litchfield, and State of Connecticut, have invented a new, original, and ornamental Design for a Slider for Fastening Elements, of which the following is a specification, reference being had to the accompanying drawing, forming part thereof, wherein:—

Fig. 1 is a front view of a slider for fastening elements showing my new design.

Fig. 2 is a rear view of the same with the button element inserted in the face of the tab in Fig. 1 removed.

Fig. 3 is a side view.

I claim:

The ornamental design for a slider for fastening elements, as shown and described.

ALDEN G. STEVENS.
